UNITED STATES PATENT OFFICE

JOHN L. McMILLAN, OF SYRACUSE, NEW YORK, ASSIGNOR TO McMILLAN BOOK COMPANY, OF SYRACUSE, NEW YORK, A CORPORATION OF NEW YORK

VISIBLE INDEX BINDER

Application filed June 4, 1928, Serial No. 282,736. Renewed July 30, 1930.

This invention relates to a new and improved loose leaf binder of the type usually called a visible index binder.

When a loose leaf binder is used as a visible index the sheets in the binder are narrower than the binder itself so that they may be placed in the binder in overlapping relation. This assembly permits the insertion of sheets in such a way that a portion of each sheet is at all times exposed to view, such portions carrying any desired indicia for the purpose of indexing the sheets.

In using a visible index of this character it is necessary from time to time to remove a sheet from the binder and to add a new sheet to take the place of the one removed. When this is done it is usual to move upward in the book the sheets which were in position beneath the sheet removed so that the new replacing sheet may be placed at the bottom of the binder.

In order to facilitate the transfer of sheets from one position in a binder to another position in the binder various devices have been constructed by the use of which sheets may be transferred from one set of prongs to another set of prongs while they are retained at all times on prongs. In all the devices of the latter character known to the art the distance which a sheet may be moved in a binder is limited by the character of the means supplied for accomplishing the transfer so that if it is desired to move a sheet a greater distance than the device will permit it is necessary to repeat the transferring operation one or more times.

The main object of my invention is to provide in a visible index a transferring device which will permit the transfer of sheets from one position in the binder to any other position in the binder by one transferring operation irrespective of the distance which it is desired to move the sheet.

Other objects and advantages relate to the size, shape and association of parts all as will more fully appear from the following description taken in connection with the accompanying drawings in which:—

Figure 1 is a perspective view, partially

broken away, of my binder in the closed position.

Figure 2 is a section on line 2—2 of Figure 1.

Figure 3 is a section on line 3—3 of Figure 6.

Figure 4 is a section similar to Figure 2 with the binder in the open position to permit the removal or insertion of sheets.

Figure 5 is a section on line 5—5 of Figure 2.

Figure 6 is a top view, partially broken away, of my device in the position shown in Figure 3.

Figure 7 is a perspective view of my prong-carrying plate with the prongs partially cut away.

Figure 8 is a perspective view of my locking slide.

My device may be used in conjunction with any type of loose leaf binder which has opposed sets of prongs which are movable to and from each other but for the purpose of showing my device in combination with a loose leaf binder I have here shown a type of binder in which a back member —1— is hingedly connected to an opposing back member —2—. On the upper face of back member —1— I provide a top plate —3—. A vertically extending back plate —4— is secured to the outer longitudinal edge of back member —1— by screws, not shown, or other convenient means. The upper edge of back plate —4— is return bent to form a plurality of spaced eyes 5—5 to receive therebetween the eyes —6— of a cover —7— to form in combination with eyes —5— and —6— and pintle —8— a piano hinge. A prong carrying plate —9— is affixed to the inner face of back member —4— by rivets —10— or other convenient means. A plurality, in this case shown as five, of arcuate rods or prongs —11— are secured to the inner longitudinal face of prong-carrying plate —9— adjacent the top thereof. Prong-carrying plate —9— has a plurality of spaced notches —13— on its upper edge for a purpose hereinafter to be described.

Back member —2— carries a top plate —14— on its upper face and is provided with

a vertically extending back plate —15— affixed to its outer longitudinal edge by screws, not shown, or other convenient means. Back plate —15— has its upper edge bent inwardly to form a longitudinally extending slot —16— for a purpose hereinafter to be described. A hinge member —17— is affixed to the outer face of the top longitudinal edge of back plate —17—. Hinge member —17— is provided with a plurality of spaced eyes —18— coacting with a plurality of spaced eyes —19— on cover —20—. Eyes —18— and —19— and pintle —21— coact to form a piano hinge. A locking slide —22— having a plurality, in this case shown as four, of slots —23— and a plurality, in this case shown as four, of evenly spaced upwardly extending and forwardly offset spaced tabs or ears —24— is slidably mounted on the inner face of back member —15— at its lower longitudinal edge and is held in slidable position by means of headed rivets —25— which extend inwardly from the inner face of back plate —15—. Back plate —15— is also provided with a plurality, in this case shown as four, of positioning lugs —26— for a purpose hereinafter to be described. A prong-carrying plate —27— has affixed to the upper longitudinal edge thereof a plurality, in this case shown as five, of spaced prongs —28— and is provided on its bottom longitudinal edge with a series, in this case shown as nineteen, of spaced notches —29— of a size to receive positioning lugs —26— and also of a size to permit the passage therethrough of ears —24—. In order to assemble prong-carrying plate —27— on back member —2— I pull outwardly locking slide 22 by means of handle —30— to the position shown in dotted lines on Figure 5. I then place prong-carrying plate —27— in position on back member —2— with its upper longitudinal edge in slot —16— with positioning lugs —26— in position in the proper slots —29— to place prong-carrying plate —27— with its ends in the same plane as the ends of prong-carrying plate —9—. This positioning of prong-carrying plate —27— is permitted due to the fact that ears —24— are so positioned that they will pass through slots —29— in prong-carrying plate —27—. When prong-carrying plate —27— is so positioned I push locking slide —22— inwardly which will position each ear —24— between two slots —29— and abutting against the inner face of prong-carrying plate —27— so that prong-carrying plate —27— will be locked in position on back member —2—.

For the purpose of releasably securing back members —1— and —2— in selected positions in relation to each other I provide in back member —1— a pair of spaced latches —31— and —32— which extend inwardly into apertures —33—, one only being shown in Figure 6. Latches —31— and —32— are

provided with a plurality, in this case shown as three, of notches —34—, two only being shown in Figure 6 on latch —31—. A keeper —35— is slidably mounted in back member —2— and is provided with a pair of spaced slots —36— and —37— so positioned that when keeper —35— is in the normal position it will engage notches —34— in latches —31— and —32— to hold back members —1— and —2— in fixed relation. A spring —38— has one end attached to keeper —35— and has the other end attached to back member —2— and is positioned so that it will releasably hold keeper —35— in the normal or locking position.

When it is desired to transfer a sheet —39— in the binder by the use of my device the sheet is placed on the prongs —28— carried by the prong-carrying plate —27—. The keeper —35— is then pushed inwardly to release latches —31— and —32— and the binder is opened to the intermediate position shown in Fig. 6, the keeper —35— being released so that it will engage latches —31— and —32— to lock the binder in that position. Locking slide —22— is then pulled outwardly to the position shown by dotted lines in Figure 5 to permit the removal from the binder of prong-carrying plate —27—. Prong-carrying plate —27—, carrying with it sheet —39—, is then moved vertically of the binder and again inserted therein and locked in position by locking slide —22— in the manner heretofore described. The sheet —39— is then transferred to the prongs —11— carried by the back member —1—. Prong-carrying plate —27— is then released from locking slide —22— and removed from the binder. It is then reinserted in the binder in the normal position and the binder is closed.

I have indicated in dotted lines on Figure 6 one position of prong-carrying plate —27— when it has been moved vertically in the binder. It will be apparent that when the prong-carrying plate —27— is in the normal position, as shown in heavy lines on Figure 6, a prong —11— on back member —2— would, when the binder was closed, enter a hole —40— in sheet —39—. If, however, the prong-carrying plate —27— is moved vertically in the binder to the position shown by dotted lines in Figure 6, and the binder is then closed the prong —11— will enter the hole —41— in sheet —39— with the result that when sheet —39— has been transferred to the prongs —11— carried by back member —1— and the prong-carrying plate —27— returned to its normal position the sheet —39— will have been moved vertically the distance between two holes in the sheet —39—.

The notches —13— in ring-carrying plate —12— are so positioned that when the binder is in the closed position as shown in Figure 1 the ends of the prongs —28— carried by prong-carrying plate —27— will enter the

notches —13—. Similarly notches —42— are provided in the upper edge of back plate —15— into which the ends of prongs —11— enter when the binder is in the closed position.

It will be obvious that prong-carrying plate —27— may be moved as long or as short a distance in the binder as may be desired and that the distance which a sheet —39— is transferred vertically in the binder may be varied at will. It will also be obvious that the sheet —39— may be moved in either direction with respect to back member —1—.

It will also be obvious that the exact type and design of the binder with which my device is used may be varied as may be the method of operation of the binder with which my device is used for although I have shown and described a specific structure and form of part as an exemplification of an embodiment of my invention I do not desire to restrict myself to the exact size and shape or arrangement of parts as various changes may be made within the scope of the appended claims.

What I claim is:

1. In a device of the class described, a prong support, a plurality of prongs secured to such support, a second prong support in opposed relation to the first named prong support, a plate having a plurality of prongs affixed thereto and having a plurality of spaced notches in one longitudinal edge, a slide mounted on the second-named prong support, and a plurality of spaced tabs on one longitudinal edge of the slide adapted in one position of the slide to overlie the plate to secure it on the prong support and adapted in another position of the slide to register with the notches in the plate to permit the removal of the plate from the prong support.

2. In a device of the class described, a prong support, a plurality of prongs secured to such support, a second prong support in opposed relation to the first-named prong support, a plate having a plurality of prongs affixed thereto and having a plurality of spaced notches in one longitudinal edge and the second named prong support being formed with a longitudinally extending slot adapted to receive the other longitudinal edge of the plate, a slide mounted on the second-named prong support, and a plurality of spaced tabs on one longitudinal edge of the slide adapted in one position of the slide to overlie the notched edge of the plate to secure it on the prong support and adapted in another position of the slide to register with the notches to permit the removal of the plate from the prong support.

3. In a device of the class described, a prong support, a plurality of prongs secured to such support, a second prong support in opposed relation to the first-named prong support, a plate having a plurality of prongs

affixed thereto, and means for positively locking the plate on the second-named prong support in a selected one of a plurality of different positions relative to such prong support.

In witness whereof I have hereunto set my hand this 28th day of May, 1928.

JOHN L. McMILLAN.
